COOLING APPARATUS

Rudolph J. Eisinger, Prospect Park, Pa., assignor to Westinghouse Electric & Manufacturing Company, East Pittsburgh, Pa., a corporation of Pennsylvania

Application July 1, 1936, Serial No. 88,296

6 Claims. (Cl. 62—2)

My invention relates to refrigerating apparatus, and it has for an object to provide improved apparatus.

More particularly, the invention relates to 5 refrigerating apparatus of the steam jet type in which cooling of liquid is effected in successive stages. Such apparatus comprises a plurality of evaporator chambers through which the liquid to be cooled is conveyed in series. An ejector, usually steam motivated, is provided for each evaporator chamber for removing vapor therefrom. The removal of vapor from the evaporator chamber effects reduction of pressure therein, so that the liquid passing therethrough is partially 10 vaporized and cooled. A common condenser may be provided for the several ejectors. In such case, if operation of one of the ejectors is terminated, the vapor pressure in the associated evaporator chamber is raised to that of the condenser, due 15 to flow of vapor through the ejector, thereby subjecting any liquid within the chamber to the higher temperature of such higher pressure vapor.

It is an object of my invention to prevent 20 heating of liquid in the chamber whose ejector is not in operation while another ejector is in operation.

Another object of my invention is to vary the 25 amount of cooling action in accordance with the cooling demand.

In accordance with my invention, I provide 30 conduit and valve means for by-passing the liquid to be cooled around any evaporator chamber whose ejector is not in operation. In this way, it is not subjected to the higher temperature of 35 the condenser vapor pressure in such evaporator chamber. Preferably, the evaporator chambers are arranged at successively lower levels, so that the liquid to be cooled flows by gravity from one 40 chamber to the next and the connecting conduits are formed to provide loop seals between successive chambers.

I also provide control mechanism for initiating 45 operation of the several ejectors successively in response to successive increases in refrigerating load, which may be indicated by successive increases in the temperature of the liquid being cooled.

The above and other objects are effected by 50 my invention, as will be apparent from the following description and claims taken in connection with the accompanying drawing, forming a part of this application, in which:

55 Fig. 1 is a diagrammatic elevational view of

refrigerating apparatus embodying my invention; and,

Fig. 2 is a plan view thereof showing the ejectors and the common condenser.

Referring to the drawing in detail, I show 5 steam jet refrigerating apparatus for supplying cooled liquid, such as water, to any apparatus in which it may be required. Such apparatus may be, for example, the air cooler and washer of air 10 conditioning apparatus, shown on the drawing 15 at 9.

The refrigerating apparatus comprises a first evaporator chamber 10 and a second evaporator 11. In the present embodiment, these chambers are formed by separate tanks. Steam motivated 15 ejectors 12 and 13, shown in Fig. 2, have their suction inlets 12' and 13' connected to the chambers 10 and 11, respectively, and effect a vacuous or reduced pressure condition in the respective chambers by withdrawing vapor therefrom. The 20 ejectors 12 and 13 are motivated by steam from a supply conduit 14, the admission thereof being controlled by valves 15 and 16, respectively, the operation of which is described later. The ejectors exhaust into a common condenser 17, which 25 is provided with a condensate outlet 18, an air outlet 19 connected to an air ejector 20, a cooling water inlet 21, and a cooling water outlet 22.

For full load operation, both ejectors are operated, and for partial load operation, only the 30 ejector 13 is operated, the ejector 12 being shut down by closing the valve 15. The condenser pressure is then admitted into the chamber 10 through the ejector 12.

The water to be cooled is conveyed, in this 35 case, from the air cooler and washer 9, by a conduit 23 to a three-way valve 24. The latter has one outlet connected to spray nozzles 25 provided in the evaporator chamber 10, and a second outlet connected to a by-pass conduit 26. The 40 water cooled in the chamber 10 is discharged therefrom through an outlet in the bottom, which outlet is connected to a looped conduit 27 formed to provide a manometric connection or loop seal comprising vertical portions 27a and 27b and a 45 horizontal portion 27c connecting the lower ends of the vertical portions. The upper end of the vertical conduit portion 27b and the lower end of the by-pass conduit 26 are connected through a T-fitting 28, to a conduit 29 leading to spray 50 nozzles 30 provided in the evaporator chamber 11. The water cooled in the evaporator chamber 11 is discharged therefrom through an outlet in the bottom to a conduit 31, from which it flows to a pump 32. The latter delivers the same under 55

pressure to a conduit 33, through which it is delivered to the point of use, in this case, the air cooler and washer 9. In the latter, the water absorbs heat from the air passing therethrough. 5 It is discharged therefrom at increased temperature to the conduit 23 to be recirculated.

Control mechanism for regulating the operation of the refrigerating apparatus is provided. It includes solenoids 34 and 35 for opening the valves 10 15 and 16, respectively, the latter being biased to closed position in any suitable manner, as by springs. A solenoid 36 controls the valve 24, which is biased to the position in which it conveys water to the by-pass conduit 26, and which 15 is operated to convey the water to the nozzles 25 of the chamber 10 when the solenoid 36 is energized. The solenoids 34 and 36 are controlled by contacts 37, and the solenoid 35 is controlled by contacts 38. Electric current for energizing the 20 solenoid is supplied by line conductors L₁ and L₂ through the connections which are shown on the drawing and which are readily understood therefrom.

The contacts 37 and 38 are controlled by a 25 thermostat 39 in response to the temperature of the liquid to be cooled, taken at any desired point in the circuit or path thereof. Preferably, and as shown, the thermostat includes an expansible bellows 41 connected by a tube 42 to a bulb 43 30 disposed in the conduit 31 in which it is subjected to the temperature of the cooled water. The thermostat 39 is arranged to close the contacts 38 in response to a predetermined maximum temperature, to close both contacts 37 and 38 in response to a slightly higher predetermined maximum temperature, and to open both contacts 37 35 and 38 in response to a temperature lower than the first-mentioned predetermined maximum temperature. For the purpose of an example, 40 the first and second predetermined maximum temperatures will be taken as 40° and 41° F., respectively.

Make-up water to replace the water which is vaporized and removed by the ejectors is supplied 45 through a conduit 44. The latter is connected to the water circuit at any suitable point, for example, at the T-fitting 28. The admission of make-up water is controlled by a valve 45 connected in the conduit 44, which valve is controlled 50 by a float control 46 in response to the level of water in the chamber 11. The float control 46 is connected to the valve 45 to actuate the same in any suitable manner, as by means of a hydraulic connection 47.

55 The operation of the above-described apparatus is as follows:

Assume the air cooler or other refrigerating load requires the maximum amount of refrigeration. This is evidenced by a temperature of the 60 cooled water of 41° F. or higher. The thermostat 39 closes the contacts 37 and 38 to effect energization of all of the solenoids, thereby rendering both ejectors operative and adjusting the valve 24 to admit the water to the chamber 10. Upon being subjected to the vacuum or decreased pressure in the evaporator chamber 10, the water is 65 partially vaporized, which action effects cooling of the remaining water, as is well known in the art. Preferably one half of the temperature reduction 70 of the water is effected in the chamber 10. The water then flows by gravity through the looped conduit 27, the T-fitting 28 and the conduit 29 to the chamber 11, the difference in level between the chambers providing sufficient head 75 to force the water through the nozzles in the

chamber 11. The remainder of the temperature reduction of the water is effected in the chamber 11, by partial evaporation of the water as described above, and the water is then discharged therefrom into the conduit 31. It is then conveyed from the pump through the conduit 33 to the cooler 9. 5

As the requirement for refrigeration decreases, the temperature of the water decreases; however, the contacts 37 will be kept closed and the apparatus maintained at full load operation until the temperature drops below 41° F., or a slightly lower temperature, indicating that one-half load operation will supply the needed refrigeration, at least temporarily. The contacts 37 are then 10 opened, deenergizing the solenoids 34 and 36. Operation of the ejector 12 is terminated and the valve 24 is moved by the spring to the position shown on the drawing, in which the water from the conduit 23 is delivered to the by-pass 20 conduit 26. The latter conveys the water to the nozzles 28 of the chamber 11.

As the ejector 12 is shut down, the vapor in the condenser is free to flow through the ejector 12 to equalize the vapor pressure in the condenser 25 and in the evaporator chamber 10. Due to its higher pressure, this vapor is also of higher temperature and would heat no water in the chamber 10 with which it comes into contact. The looped conduit 27 provides a loop seal to prevent 30 the escape of this higher vapor pressure from the chamber 10 into the chamber 11. The chamber 10 is disposed at a sufficiently higher level than the chamber 11 so that all of the water from the chamber 10 flows into the conduit 27, so 35 that there is no water therein to be heated by the higher vapor pressure. Due to the relatively small cross section of the conduit portion 27a, the surface of the liquid therein subject to the higher temperature of the vapor in the chamber 40 10 is very small and the amount of heating is negligible. Furthermore, the water subjected to the heating is in a relatively static condition. In this case, then, the water to be cooled by-passes the chamber 10 and is admitted directly into the 45 chamber 11 in which a single stage of temperature reduction is effected. It is then delivered to the air cooler 9 or other point of use in the same manner as before.

If the refrigeration requirement is substantial- 50 ly less than full load and greater than half load, there will be intermittent full load and half load operation, the temperature of the water decreasing during the full load operation and increasing during the half load operation. 55

If the temperature of the water drops below 40° F., or a slightly lower temperature, indicating that no further refrigeration is presently needed, the contacts 38 are also opened, shutting down the ejector 13. The water is then circulated 60 through the chamber 11 without any cooling except for the action of the air ejector 20 of the condenser, which effects a small amount of evaporation water. Upon subsequent increase in temperature of the water, the contacts 38 will 65 reclose, and cooling at half load will be resumed. Thus, a load less than half load is taken care of by intermittent half load operation.

It will thus be seen that I have provided an arrangement whereby heating of the water in an 70 evaporator chamber containing vapor at condenser pressure is prevented. It will also be seen that I have provided automatic control mechanism whereby the amount of cooling may be varied in accordance with the cooling load. 75

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

10. What I claim is:

1. In refrigerating apparatus, the combination of a plurality of evaporator chambers, an ejector associated with each chamber for withdrawing vapor therefrom, and means responsive to a predetermined load condition for conveying liquid to be cooled through a plurality of said chambers in series and for effecting operation of the ejectors associated therewith and responsive to a lighter predetermined load condition for conveying said water through only one of said chambers and for effecting operation only of the ejector associated with said one chamber and including means for directing the liquid into the vapor-containing space of each chamber and subjecting the liquid to the reduced pressure in such space.

2. In refrigerating apparatus, the combination of first and second evaporator chambers, an ejector associated with each chamber for withdrawing vapor therefrom, a common condenser for said ejectors, means for delivering liquid to be cooled to said first chamber, means for conveying said liquid from said first chamber to said second chamber, means for withdrawing said liquid from said second chamber, and means for by-passing said liquid from said delivery means around said first chamber to said conveying means for operation at partial load, said second chamber being disposed below said first chamber a sufficient distance so that said first chamber is emptied of water by gravity flow into said conveying means when the ejector associated with said first chamber is not in operation.

45. 3. The method of refrigerating which comprises conveying liquid to be cooled through a plurality of evaporator chambers in series for full load operation, at the same time removing vapor from each of said chambers to effect cooling of said liquid in said chambers in successive steps, and conveying said liquid through one of said chambers and by-passing another thereof for partial load operation, at the same time removing vapor from said one chamber and discon-

tinuing the removal of vapor from said other chamber, the liquid being directed into the vapor-containing space of each chamber through which it is conveyed and subjected to the reduced pressure in such space.

4. The method of refrigerating which comprises conveying liquid to be cooled through a plurality of evaporator chambers in series and exhausting vapor therefrom in response to a predetermined maximum temperature of the cooled liquid, and conveying said liquid through a smaller number of such chambers and exhausting vapor therefrom, while by-passing the remaining chamber or chambers, in response to a lower predetermined maximum temperature of the cooled liquid, the liquid being directed into the vapor-containing space of each chamber through which it is conveyed and subjected to the reduced pressure in such space.

5. In refrigerating apparatus, the combination of a plurality of evaporator chambers, a vapor motivated ejector or ejectors associated with each chamber for removing vapor therefrom to effect cooling of liquid by partial evaporation thereof, means for rendering the ejector or ejectors of one chamber operative or inoperative, means for conveying liquid in series through the vapor-containing spaces of said chambers and subjecting the liquid to the reduced pressures in such spaces, and means operable automatically to by-pass liquid around said one chamber upon the ejector or ejectors associated therewith being rendered inoperative.

6. In vapor jet refrigerating apparatus, the combination of a plurality of evaporator chambers, a vapor motivated ejector connected to each chamber for removing vapor therefrom, means for controlling the operation of said ejectors individually, means for condensing the vaporous fluid exhausted from said ejectors, means for conveying the liquid to be cooled through said chambers in series or for conveying said liquid through one of said evaporator chambers and by-passing a second evaporator chamber, said last-mentioned means directing the liquid into the vapor-containing space of each chamber through which the liquid is conveyed and thereby subjecting it to the reduced pressure in such space, and means providing a liquid seal between said chambers when conveying liquid through said one evaporator chamber and bypassing a second evaporator chamber.

RUDOLPH J. EISINGER.
